UNITED STATES PATENT OFFICE.

REUBEN HALEY, OF BEAVER, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A SHADE.

46,816.

Specification for Design.

Patented Jan. 5, 1915.

Application filed July 29, 1914. Serial No. 853,962. Term of patent 7 years.

To all whom it may concern:

Be it known that I, REUBEN HALEY, a citizen of the United States, and residing at Beaver, in the county of Beaver and State of Pennsylvania, have invented a certain new, original, and ornamental Design for a Shade, of which the following is a specification, reference being had to the drawings, forming a part thereof and illustrating my new design, in which—

and Figs. 2 and 3 are sectional plan views of half of the shade, taken on lines 2—2 and 3—3, respectively, of Fig. 1.

I claim:

The ornamental design for a shade, substantially as shown.

REUBEN HALEY.
